(57) **CLAIM**

The ornamental design for a hanging storage container, as shown and described.

DESCRIPTION

FIG. 1 is a front view of a first embodiment of a hanging storage container showing my new design;

FIG. 2 is a rear view thereof;

FIG. 3 is a left side view thereof, the right side being a mirror image;

FIG. 4 is a top view thereof;

FIG. 5 is a top view of a second embodiment thereof;

FIG. 6 is a bottom view thereof;

FIG. 7 is a perspective front view thereof; and,

FIG. 8 is a perspective front view of the second embodiment thereof.

The broken lines illustrate portions of the hanging storage container and form no part of the claimed design. The strap is shown with a symbolic break in its length. The appearance of any portion of the article between the symbolic break forms no part of the claimed design.

The front, rear, left, right, and bottom view of the second embodiment is identical to the first embodiment.
